(57) **CLAIM**

The ornamental design for a see-through air cleaner for a motorcycle, as shown and described.

DESCRIPTION

FIG. 1 is an isometric front view of my see-through air cleaner for a motorcycle taken from the front at a side angle.

FIG. 2 is a perspective view taken from the rear at a side angle.

FIG. 3 is a front view.

FIG. 4 is a rear view; and,

FIG. 5 a side view taken from the right side of the air cleaner as seen in FIG. 3. The left side view of the air cleaner shown in FIG. 3 is a mirror image of FIG. 5.
